UNITED STATES PATENT OFFICE.

MARK V. DERRICK, OF LOS ANGELES, CALIFORNIA.

TOOTHPICK DISPENSER.

Application filed September 9, 1925. Serial No. 55,373.

So far as I am aware there has heretofore been no satisfactory means for dispensing toothpicks that will meet all requirements of sanitation, economy and convenience.

Heretofore it has been customary to make toothpicks available to users both in public and private, by placing the toothpicks in a receptacle having an opening at the top or at some other portion of the receptacle to allow the toothpicks to be removed by taking hold of them at the middle or at the end, and conveniently and without waste separating them either one at a time or in a bundle or bunch by means of the fingers of the intending user.

It is desirable that the toothpicks be protected from dust and other impurities in the air and it is also desirable to prevent intending users from taking a quantity of toothpicks in excess of those intended for immediate use.

In restaurants, hotels, lunch counters, and other public eating places where toothpicks are made immediately available to the public, considerable loss to the proprietor of such places arises from the customers taking considerable bunches of toothpicks, and an object of this invention is to prevent such losses.

I have discovered that toothpicks can be served in a satisfactory manner by loosely confining a bundle of toothpicks, giving them a semi-rotative impulse endwise of the bundle and intercepting the majority of the toothpicks in the bundle while allowing other toothpicks to be projected endwise from the bundle in separated positions; and by this method I am able to project one or more toothpicks in individual positions where they can be grasped by the fingers and drawn out of the bundle, individually without handling any of the remaining toothpicks.

The most satisfactory means I have devised for practicing this novel method and effecting the desired result consists in a container having a diameter less than the length of the conventional wooden toothpick, and a height slightly greater than the length of such toothpick; and the container is provided with a flat head having round perforations therethrough, each of which perforations is of sufficient diameter to allow a toothpick to be drawn therethrough; and preferably the walls of the container are of transparent material through which the toothpicks may be seen, and the container

is of such diameter that a single toothpick contained therein will be held alsant when the container is upright.

The container may be of any desired cross sectional form, but at present, I deem a circular cross section to be preferable and the open top is substantially of the same internal diameter as the body, the internal wall of the neck portion being relatively straight and preferably the body is contracted at the middle to cause the loose bundle of toothpicks therein to spread out at top and bottom and assume a more or less spiral arrangement when the container is upright; and in upright position of the container, the toothpicks will be on end either aslant or upright and will have a general axial extension toward the head and bottom of the container.

Such middle contraction may also afford a convenient hand-hold for the dispenser.

An advantage of this toothpick dispenser is that the user has the satisfactory assurance that the toothpick he selects is free from contamination by the fingers of other users.

Other objects, advantages and features of invention may appear from the accompanying drawing, the subjoined detailed description and the appended claims.

The improvement in the art, and the newly invented means for performing the same may be understood from the accompanying drawing.

Figure 1 is a perspective view illustrating this improvement in dispensing toothpicks.

Fig. 2 is a perspective view of the newly invented dispenser adapted to this art; showing an upright position of the dispensing means shown in Fig. 1.

Fig. 3 is an axial section of the dispenser shown in Figs. 1 and 2, while upright. A bundle of toothpicks is shown in place.

Fig. 4 is an end view of the dispenser shown in Figs. 1, 2 and 3.

The container in the form shown, is made of glass, open at the top and being formed with a neck 2, the interior wall 2' of which is relatively straight and the exterior wall provided with screw threads 3. The container is internally contracted at the waist or middle as indicated at 4, thereby forming an outwardly bulged portion 4' immediately below the neck 2 and likewise, by reason of such contraction, the lower end of the container is outwardly bulged at 4''. The base of the container is concaved at 4''' and a screw threaded head or closure 5, is adapted

to be screwed upon the threaded portion 3 of the neck and is provided preferably with round perforations 6 of sufficient diameter to allow the toothpicks 7 to be projected therethrough and to be drawn therethrough from a bundle of toothpicks 8 in the container.

The container and head may be of any suitable material and in the form shown in 10 the drawing, the head may be of thin spun metal or of celluloid and the container may be of glass, celluloid or other convenient material and is preferably transparent as indicated, so that a loose bundle of toothpicks 15 may be visible at all times, as indicated in Figs. 1, 2 and 3.

In practice a loose bundle 8 of toothpicks will be inserted into the container and the head will then be secured in place. The 20 toothpicks resultant of the outwardly bulged upper and lower portions, will be disposed aslant, with their opposite ends positioned within the upper and lower concavities formed by the bulged portions 4' and 4'', 25 while the picks at the center of the bundle 8, will rest upon the concave portion 4''' of the base, effecting a relatively spiral assembly of the picks within the said container.

The operator, grasping the container, will 30 give it a forward movement, preferably in horizontal or in a more or less inverted position of the container, thus giving all of the toothpicks a substantially semi-rotative momentum, tending to project the bundle of toothpicks into engagement with the straight wall 2' of the neck and the greater majority of the toothpicks will be intercepted by such neck wall 2', a limited number of toothpicks will be directed through the round head perforations; and by reason of the mutual friction of the toothpicks in the loose bundle, one upon another, and also the friction of each toothpick on the margin of the hole through which it has been projected, such 45 toothpick will be retained in position to be grasped by the free hand of the operator, or by any person who may take hold of the same to draw it from the dispenser.

It is understood that the illustration in

the drawing of the means for carrying out 50 this improvement are intended merely to be conventional, and that the dispensing means may be of other forms than that which is shown in the drawing, and that the heads may be fitted onto the open end of the container by a sliding fit producing sufficient friction to hold the head in place against the impact of the bundle of toothpicks. 55

It is also understood that the invention may be used for dispensing matches or like 60 elongate bodies.

I claim:

1. A toothpick dispenser consisting of a container open at one end and contracted between its ends and provided at the open end 65 with a head having one or more round perforations adapted to permit a toothpick to be drawn therethrough; the contracted portion of the container being adapted to allow the toothpicks in the container to stand aslant 70 on end in spiral lines, and said contracted portion also serving to form a hand-hold for the purpose of holding the container while giving it momentum and also while stopping it suddenly to cause one or more toothpicks 75 of a bundle of toothpicks contained in the container to be projected by semi-rotative momentum through the head so as to be in position to be grasped by one desiring to be served with a toothpick. 80

2. A toothpick dispenser comprising a receptacle having an open neck portion and being medially contracted to form outwardly bulged upper and lower portions, said neck being provided with a straight interior wall, 85 a perforated cover adapted for connection to said neck, the outwardly bulged portions of said receptacle forming diametrically disposed concavities adapted to receive the opposite ends of a number of the toothpicks, and means for singly delivering toothpicks 90 through the cover perforations when the said receptacle is thrust endwise and suddenly stopped.

In testimony whereof, I have hereunto set 95 my hand at Los Angeles, California, this 4th day of September, 1925.

MARK V. DERRICK.
